UNITED STATES PATENT OFFICE

161,401

TROUSER HANGER

Albert E. Wurtz, Whittier, Calif.

Application February 27, 1950, Serial No. 8,175

Term of patent 14 years

(Cl. D80—8)

To all whom it may concern:

Be it known that I, Albert E. Wurtz, a citizen of the United States, residing at Whittier, in the county of Los Angeles, and State of California, have invented a new, original, and ornamental Design for a Trouser Hanger, of which the following is a specification, reference being had to the accompanying drawing, forming part thereof.

I claim:

The ornamental design for a trouser hanger, as shown.

ALBERT E. WURTZ.
